Attorney

UNITED STATES PATENT OFFICE.

ORETA L. YEOMANS, OF KIS-LYN, PENNSYLVANIA.

BRACKET.

1,350,400.

Specification of Letters Patent. Patented Aug. 24, 1920.

Application filed November 5, 1919. Serial No. 335,804.

To all whom it may concern:

Be it known that I, ORETA L. YEOMANS, a citizen of the United States, residing at Kis-Lyn, in the county of Luzerne and State of Pennsylvania, have invented certain new and useful Improvements in Brackets, of which the following is a specification, reference being had to the accompanying drawings.

10 This invention relates to certain improvements in brackets, and has relation more particularly to brackets especially designed and adapted for use for rotatably supporting shade rollers, towel rollers and the like, and it is an object of the invention to provide a novel and improved pair of brackets adapted for use in connection with a single roller, whereby the roller is effectively maintained in applied position.

20 The invention consists in the details of construction and in the combination and arrangement of the several parts of my improved bracket, whereby certain important advantages are attained and the device rendered simpler, less expensive and otherwise more convenient and advantageous for use, as will be hereinafter more fully set forth.

The novel features of my invention will hereinafter be definitely claimed.

30 In order that my invention may be better understood, I will now proceed to describe the same with reference to the accompanying drawings, wherein:

Figure 1 is a view in elevation illustrating 35 brackets constructed in accordance with an embodiment of my invention, with a roller applied thereto;

Fig. 2 is a view partly in top plan and partly in section of the structure as illustrated in Fig. 1, and,

40 Fig. 3 is a view partly in side elevation and partly in section of one of the brackets as herein embodied.

As disclosed in the accompanying drawings, R denotes a roller of the type generally employed in connection with shades, and which is rotatably supported by the brackets A and B. The bracket A is formed on the outer end of a threaded shank 1, which is adapted to be engaged in a conventional manner, with a support, such as a

window frame or the like. The drop end of the shank 1 is defined by an outstanding annular flange 2. When the bracket A is in applied position, a washer 3 of rubber 55 or other yieldable or compressible material, is inserted between said flange 2 and the adjacent surface of the support, so that the bracket when being applied will not injure or unduly mar such surface. The bracket 60 A is provided with an angular opening 8, which is adapted to receive the angular gudgeon or trunnion comprised in the well known type of shade roller.

The opposite end of the roller R is provided with the threaded trunnion 4, adapted to be engaged within the socket 5, formed in the shank 6 of a cap C. The shank 6 is loosely insertable through an opening 7 formed in the bracket B with the cap C 70 outwardly arranged with respect to said bracket. By this means it will be obvious that the roller R may be effectively supported between the brackets A and B, and in a manner whereby the roller is held 75 against displacement, and particularly as a result of a sudden jerk or pull being imposed upon the curtain or the like, coacting with the roller R.

It will also be obvious that the cap C 80 coacts with the bracket B to provide a rotatable bearing for the trunnion 4.

From the foregoing description it is thought to be obvious that a bracket constructed in accordance with my invention is 85 particularly well adapted for use by reason of the convenience and facility with which it may be assembled and operated, and it will also be obvious that my invention is susceptible of some change and modification 90 without departing from the principles and spirit thereof, and for this reason I do not wish to be understood as limiting myself to the precise arrangement and formation of the several parts herein shown in carrying 95 out my invention in practice except as hereinafter claimed.

I claim:

1. In combination with a roller provided with a threaded trunnion, a supporting bracket having an opening, and a cap provided with a shank insertable through the 100

opening of the bracket, said shank being provided with a socket to receive the threaded trunnion of the roller.

2. In combination with a roller provided with a threaded trunnion, a supporting bracket having an opening, a cap provided with a shank insertible through the opening of the bracket, said shank being provided

with a socket to receive the threaded trunnion of the roller, a gudgeon carried by the 10 opposite end of the roller, and a second supporting bracket provided with an opening to receive the gudgeon.

In testimony whereof I hereunto affix my signature.

ORETA L. YEOMANS.
